UNITED STATES PATENT OFFICE

HERMAN NEWMANN, OF BROOKLYN, NEW YORK, ASSIGNOR TO UNITED SHOE MACHINERY CORPORATION, OF PATERSON, NEW JERSEY, A CORPORATION OF NEW JERSEY

METHOD FOR USE IN THE MANUFACTURE OF TURNED SHOES

Application filed July 29, 1927. Serial No. 209,298.

This invention relates to methods for use in the manufacture of shoes, and particularly to methods for use in the making of turned shoes.

In the manufacture of that type of turned shoe known as a "sewed seat turn", the upper, wrong side out, is sewed to the sole all the way round. The sole is usually provided with a shoulder channeled about its entire periphery; that is, the margin of the flesh face of the sole is rabbeted to form a feather and a shoulder, the shoulder is usually perpendicular to the plane of the sole and the feather is at right angles to it. About the shank and heel end of the sole, if a close edge effect is desired, the angle between the feather and the shoulder may be obtuse, the feather being then inclined outwardly and toward the grain face of the sole. A slit or channel is cut in the flesh face of the sole to receive the stitches, the channel being spaced from the shoulder to provide between-substance for the stitches and inclined outwardly and toward the grain face of the sole with the bottom of the channel preferably located a distance equal to the diameter of the needle below the lower edge of the shoulder. The prepared sole is placed upon the bottom of the first last with the channel side exposed, and the upper, placed wrong side out upon the first last, is lasted over the sole and held there temporarily by a few lasting tacks driven through the lining and upper and into the between-substance. About the forepart and the part of the shank forward of the counter, the upper and lining bridge the rabbet and in the subsequent sewing operation are drawn into the rabbet by stitches against the feather and shoulder. This operation at the shank and forepart is comparatively simple since the lining and upper are flexible enough to be forced by the stitches fully into the rabbet. The shoe is held against a channel guide located in the channel and tipped about the channel guide as a fulcrum so that the needle will emerge at the lower edge of the shoulder, and the formation of a groove in the lining as the upper is drawn into the angle between the shoulder and feather indicates to the operator whether or not the shoe is being properly held.

About the heel end, however, the conditions are different since at this portion of the shoe the upper includes a counter which is usually a straight counter, that is, one which has no flange formed upon it. The counter is usually of sole leather and has the margin which is next to the sole skived to a thin edge. The counter, of course, at the time the shoe is sewed is in temper. The lining at the heel end of the shoe is turned back, exposing the counter. The counter and upper bridge the rabbet about the heel end of the shoe just as the lining and upper do at other parts of the shoe, but since the counter, even in its tempered condition, is relatively stiff and unyielding, it is difficult for the turn sewing machine operator so to position the shoe that the sewing line where the stitches are exposed on the face of the counter will be so located that the counter with the upper will be drawn into the rabbet. This is particularly difficult if the angle between the shoulder and feather is obtuse, so that no very definite angle will be formed in the counter when the shoe is being properly held. If the operator tips the shoe on the channel guide too much upwardly, he sews too high; that is, the needle emerges too far up on the shoulder so that the full strength of the between-substance is not utilized to hold the stitches and when the shoe is turned there will be a space between the upper and the feather. If he tips the shoe too far downwardly, he sews too low, with the result that the needle emerges through the feather, or even through the edge face of the sole, with the result that when turned the heel end of the shoe is ill shaped and can be reformed to the second last only by an excessive amount of hard work, if at all. Under these conditions the shoe is frequently so held to the machine that the needle sews too high or too low, with consequent detriment to the resulting product.

With a view to overcoming these difficulties, the present invention, in one of its aspects, provides a method which consists in shaping the counter to the first last and pressing the upper and counter into the rabbet to provide a well-defined sewing line about the rear end of the shoe to facilitate the sewing

operation and to enable the seam to be sewn with precision along the line where it should be located and neither too high nor too low. To this end, as herein illustrated, a heel-embracing band is utilized to shape the upper to the first last and, while the upper is so held, end-embracing wipers are utilized to force the upper and counter into the rabbet to form a groove or line about the heel end of the shoe to guide the operator in the sewing operation. With the heel end of the shoe thus prepared, the operator can tell whether or not the needle is emerging at the line formed on the outer surface of the counter and, if not, can tip the shoe to correct the sewing since the emergence of the needle on the inner side of the line will indicate that he is sewing too high, and its emergence on the outer side of the line will indicate that he is sewing too low.

After a shoe of the type referred to is trimmed and turned, the loose lining about the heel end is smoothed down inside the shoe into contact with the counter and sole, and a shank piece, which in shape is substantially a counterpart of the shank and heel portion of the sole, is inserted, a shank stiffener being usually secured to the under face of the shank piece. The shoe is then relasted upon the second last which is for the opposite foot from that of the first last. In the turning operation the shape of the counter imparted to it by the first last is reversed. However, when the counter has been shaped to the first last, as above described, and creased to form a sewing line, there is just the correct amount of material in the rear end of the shoe to receive the rear end of the second last, and the crease along the sewing line materially assists in reshaping the counter to the shape of the second last since it insures that it will bend at the sewing line and not elsewhere. As a result, the second last can be inserted more easily and the shoe fits the last much better than it would if the preliminary shaping and crease forming operations were omitted. The upper must now be reshaped into conformity with the second last and the heel end of the sole beaten down to flatten the peripheral portion of the upper where it is turned inwardly about the heel-seat. This operation is usually performed by means of a hand hammer and is a tedious and expensive operation requiring patience and skill. The counter portion is hammered by blows properly directed to set all parts of the counter against the last, and the heel end portion of the sole is hammered to flatten as well as possible the inturned portion of the upper, which, being covered by the margin or feather of the sole, cannot be engaged directly by the hammer. This hammering of the sole deflects the feather of the sole toward the upper and, in order to prepare the shoe for the next operation, that of heel-seat fit-

ting if a wood heel is to be applied, the margin of the sole has to be raised by the introduction of a dull, blade-like instrument, called a "bone" and usually made of that substance, into the crease between the feather and the upper to raise the feather so that the wipers of the heel-seat fitting machine can be introduced into the crease.

With a view to obviating or substantially reducing this hand work of shaping the upper to the last, evening the inturned portion of the upper, and opening the crease, as well as to provide for obtaining the desired results more quickly, more effectively and more accurately, the present invention, in another aspect, comprises applying shaping pressure to all parts of the heel end portion of the upper and counter to conform them to the last, opening all portions of the crease, and applying pressure heightwise of the last to the turned-in portions of the upper. Preferably and as illustrated, all portions of the parts operated upon in each of these three operations are treated simultaneously. To this end also, as illustrated, an end-embracing band is utilized for conforming all portions of the heel end of the upper and counter to the last simultaneously, and end-embracing wipers are utilized to open at once all portions of the crease between the sole and upper about the heel end and to apply pressure heightwise of the shoe directly to all parts of the inturned portion of the upper about the heel end.

In the drawings,

Fig. 1 is a sectional view of the rear end portion of a last showing the upper and counter of a turn shoe lasted over the sole;

Fig. 1^a is a view similar to Fig. 1 showing an inclined feather on the sole;

Fig. 2 is a sectional and perspective view showing the shoe of Fig. 1 after it has been treated to provide a sewing line on the counter;

Fig. 3 is a sectional view similar to Fig. 1 showing the shoe after the upper and counter have been sewed to the sole;

Fig. 4 is a sectional view of the rear portion of a turn shoe after it has been turned and relasted;

Fig. 5 is a perspective view, partly in section, showing the shoe, after it has been turned, being treated by suitable apparatus to reshape it to the last, open the crease, and flatten the inturned upper;

Fig. 6 is a sectional view of parts shown in Fig. 5; and

Fig. 7 is a fragmentary detail, in section and perspective, showing the shoe after treatment by the apparatus shown in Fig. 5.

In the drawings, Fig. 1 shows a counter 10 and an upper 12 lasted over a last 14 upon a sole 16 having a channel 18, the upper being held by a tack 20 driven into the between-substance of the sole, and a lining 22

being turned back out of the way. The margin of the sole 16 is rabbeted to form a feather 24 and a shoulder 26. The shoulder 26 is perpendicular to the plane of the sole, and the feather 24, as illustrated in Fig. 1, is at right angles to it. The feather, however, may, as illustrated in Fig. 1^a, be inclined downwardly and outwardly, as is the practice in the manufacture of some types of turn shoes. It will be noted that in either case the upper does not hug the last and that the upper and counter bridge the space between the feather 24 and the shoulder 26. It will be apparent that if the shoe were sewed with the parts referred to in the relation shown in Figs. 1 and 1^a, the tension of the stitches would not produce a sharp angle in the counter and that there would be a relatively wide region through which the needle might emerge without its being obvious to the operator that he was not holding the shoe properly.

Fig. 2 represents the shoe after treatment in accordance with the present invention to form a definite sewing line clearly apparent to the operator. This may be accomplished with the aid of the apparatus shown in Fig. 5, which comprises a last support 28, an end-embracing band 30 and end-embracing wipers 32. Treatment of the lasted shoe by this apparatus gives the result indicated in Fig. 2. The closing of the band 30 about the rear end of the last insures that the upper will be in contact with the last at all points. With the upper thus held against displacement, the wipers 32 are closed to press the counter against the feather and shoulder of the sole and form a crease or line 34 (Fig. 2) which is located along the line where the needle should emerge when the shoe is properly held. The shoe is next sewed to attach the upper to the sole all the way round by a seam 35, the lining being sewed in with the upper about the forepart and shank to the ends of the counter wings and the counter but not the lining being sewed in with the upper about the rear end, the line or crease 34 formed on the counter by the wiper enabling the operator accurately to locate the seam on the counter so that the counter and upper will be drawn against and properly held to the feather and shoulder of the sole. If the operator tips the shoe on the channel guide, which of course engages the shoe in the channel 18, too much upwardly, he will sew too high; that is, the needle will emerge above and inside the line 34. If he tips the shoe too far downwardly, he will sew too low with the result that the needle will emerge outside the line 34. By the provision of the line 34 to indicate where the needle should emerge through the counter, the operator can readily, by utilizing the line, so hold the shoe that the needle will emerge substantially at the line and he will sew neither too high nor

too low. By this method the inaccurate location of the seam frequently resulting from the use of prior methods, with consequent detriment to the resulting product, as hereinbefore indicated, is avoided and a substantial improvement in the quality of the work is produced.

After the shoe has been sewed, the first last 14 is removed and the shoe turned and the lining 22 is smoothed down inside the shoe and pasted to the counter, its lower margin lying against the inner face of the sole. A shank piece 36 is inserted and the shoe relasted on a second last 38. The shoe is now subjected again to treatment by the apparatus shown in Fig. 5. The end-embracing band 30 is closed to force all parts of the rear portions of the upper and counter simultaneously against the last and shape it to the last. The end-embracing wipers 32 are then closed, causing them to enter the crease between the feather 24 and the inwardly turned portion of the upper 12. By this action the crease about the rear end of the shoe will be opened ready to receive the wipers of the heel-seat lasting machine. Finally pressure is applied to the closed wipers 32 heightwise of the last, for example, by upward movement of the support 28, to flatten the inwardly turned portion of the upper and counter, with the result shown in Figs. 6 and 7 where it will be seen that all portions of the inturned upper about the rear end of the shoe have been flattened and brought into a single plane so that when the sole has been heel-seat fitted, by trimming away the feather 24 and the margin of the heel-seat portion of the sole on the dotted line 40 of Fig. 7, the upper is exposed and, being in a plane, is adapted to receive the rim of a wood heel, all parts of which are in the same plane.

Having thus described my invention, what I claim as new and desire to secure by Letters Patent of the United States is:

1. That improvement in methods of making turn shoes having sewed seats which consists in providing a sole having a shoulder and feather about the heel end thereof, shaping the upper wrong side out to conform snugly to the shape of the rear end of a last, forcing the margin of the upper over the feather of the sole to define a line adjacent to the shoulder along which the seam attaching the upper to the sole is to extend, sewing the upper to the sole about the heel-seat portion along said line, removing the last, turning the shoe, relasting the shoe, again shaping the upper snugly to the rear portion of the last by pressure applied to all parts of the counter portion of the upper simultaneously, raising the feather of the sole about the heel-seat to open the crease between the upper and the sole, and flattening the peripheral portion of the upper that extends over the heel-seat portion of the shoe. 130

2. That improvement in methods of making turn shoes having sewed seats which consists in shaping an upper and counter wrong side out to conform snugly to the shape of the rear end portion of a first last and forcing its margin over the margin of a sole about the periphery of the heel-seat to define a line on which the seam attaching the upper to the sole is to extend, sewing the upper to the sole along said line, removing the last, turning the shoe, relasting the shoe, thereafter shaping the upper snugly to the end portion of the second last by pressure applied to all parts of the counter portion of the upper simultaneously, raising the margin of the sole about the heel-seat to open the crease between the upper and the sole, and flattening the portion of the upper that extends over the periphery of the heel-seat portion of the last.
3. That improvement in methods of making turn shoes having sewed seats which consists in shaping an upper wrong side out to conform snugly to the shape of the rear end of a last, simultaneously wiping in all portions of the margin of the upper at the end and sides of the heel-seat over the feather of a sole by use of wiper plates having curved edges to define a line on which the seam attaching the upper to the sole is to extend, sewing the upper and counter to the heel-seat portion of the sole, removing the last, turning the shoe, relasting the shoe, shaping the upper and counter snugly to the rear end portion of the last by pressure applied at various parts of the counter portion of the upper simultaneously, and opening the crease between the upper and the feather of the sole by insertion of a curved wiper plate, and simultaneously flattening the portions of the upper and counter that extend over the periphery of the heel-seat portion of the last.
4. That improvement in methods of making turn shoes having sewed seats which consists in providing a sole having a shoulder and a feather about the heel end, shaping the upper wrong side out to conform snugly to the rear end of a last, forcing the margin of the upper over the feather of the sole to define a line adjacent to the shoulder along which the seam attaching the upper to the sole is to extend, and sewing the upper to the sole about the heel-seat portion while utilizing said line to determine the proper location of the seam.
5. That improvement in methods of making turn shoes having sewed seats which consists in shaping an upper and counter wrong side out to conform snugly to the shape of the rear end portion of a first last, forcing its margin inwardly over the periphery of the heel-seat of the sole to define a line on which the seam attaching the upper to the sole is to extend, and sewing the upper to the sole along said line.
6. That improvement in methods of making turn shoes having sewed seats which consists in providing a sole having a feather and shoulder about the heel-seat portion thereof, placing wrong side out upon a last the sole and an upper having a counter, shaping the upper and counter to conform snugly to the rear end of the last, wiping the margin of the upper over the feather of the sole by use of a plate having a plane surface and a curved edge to define a line on which the seam attaching the upper and counter to the sole is to extend, and sewing the upper and counter to the heel-seat portion of the sole while utilizing the said line to indicate the proper location of the seam where it emerges on the surface of the counter.
7. That improvement in methods of making sewed seat turn shoes which consists in sewing the upper and counter to a sole about the heel-seat, turning the upper, relasting and shaping the upper and counter into intimate contact with the last about the rear end of the last, and flattening the turned-in portion of the upper and counter to bring all parts thereof into the same plane.
8. That improvement in methods of making sewed seat turn shoes which consists in sewing the counter and upper wrong side out to the periphery of the heel-seat portion of the sole, removing the last, turning the upper and counter, inserting a shank piece, relasting the shoe, conforming under pressure all portions of the counter and the upper in the region of the counter to the shape of the rear portion of the last, and, while maintaining such pressure, applying pressure heightwise of the last directly to all portions of the upper and counter extending over the heel-seat to dispose all parts of the heel-engaging portions of the surface thereof in the same plane.
9. That improvement in methods of making sewed seat turn shoes which consists in subjecting all portions of the counter portion of an upper after relasting to simultaneous pressure and while maintaining such pressure separating the margin of the sole from the upper and subjecting the inwardly disposed portions of the upper and counter about the periphery of the heel-seat to pressure heightwise of the last by use of a plate having a plane surface to engage the upper and a curved surface to enter the crease between the upper and the margin of the sole.
10. That improvement in methods of making sewed seat turn shoes which consists in sewing an upper to a sole about the heel-seat portion thereof, turning the upper, relasting the shoe, shaping the upper into intimate contact with a last about the rear end portion thereof, and subjecting the turned-in portions of the upper and counter to pressure applied simultaneously at all points about the periphery of the heel-seat to dispose the outer

surface of the turned-in portion of the upper in a plane to receive the peripheral rim of a wood heel.

11. That improvement in methods of making sewed seat turn shoes which consists in sewing an upper to a sole about the heel-seat portion thereof, turning the upper, relasting the shoe, pressing all portions of the upper about the rear end portion of the last simultaneously into contact with the last by use of a flexible end-embracing element, and flattening the turned-in portions of the upper and counter by pressure applied heightwise of the last by use of heel-embracing wipers.
15. That improvement in methods of making sewed seat turn shoes which consists in sewing a counter and an upper wrong side out to the periphery of the heel-seat portion of a sole, removing the last, turning the upper and counter, inserting a shank piece, relasting the shoe, conforming under pressure all portions of the counter and the upper in the region of the counter to the shape of the rear portion of the last, and, while maintaining such pressure, applying pressure heightwise of the last to the peripheral portion of the upper and counter to set it in position to receive the corresponding surface of a wood heel and form a tight joint between the heel and upper.
20. 13. That improvement in methods of making sewed seat turn shoes which consists in subjecting all portions of the counter portion of an upper after relasting to simultaneous pressure, and, while maintaining such pressure, separating the feather of the sole from the upper and subjecting the inwardly disposed portions of the upper and counter about the periphery of the heel-seat to pressure heightwise of the last.
